PREPAYMENT METER

Paul Moos, Zug, Switzerland, assignor to Landis &
Gyr, A. G., a corporation of Switzerland

Application June 19, 1942, Serial No. 447,727
In Switzerland August 22, 1941

10 Claims. (Cl. 194—17)

In recent times prepayment meters for dispensing electricity, gas and other commodities have been greatly simplified. The handle for manually operating the apparatus has been done away with, so that the consumer has merely to place the money in the apparatus for it to function automatically. Although such apparatuses are undoubtedly an advance on previous ones, they are still susceptible of improvement, inasmuch as they either require the use of an electric or other power motor to perform the operations, or else require positive control of the coin in the coin passage. The use of a motor makes the apparatus more expensive and, due to the constant consumption of electricity or other energy, imposes an additional financial burden on the consumer, while positive control of the coin calls for a complex construction of the coin passage and accessories cooperating therewith to perform the working cycle of the motion transmitting parts and to control the quantity-supply device. Moreover, in the use of a motor the coin operates the mechanism by its fall either by dropping onto a constantly revolving drum or by coupling two drum halves together, or by making a contact to control a circuit for supply of current to the motor, all of which may easily cause sticking of the coin at some point in its path of movement. With positive control of the coin in the coin passage, as is especially the case with apparatus built for coins of different values, the structure of the apparatus is also such as to require an inclosing housing of large dimensions.

One object of the present invention is to provide a novel construction of coin operated prepayment mechanism which overcomes these objections to prior mechanisms of this character.

Another object of the invention is to provide a coin operated prepayment mechanism in which the weight of a dropping coin and an impelling force imparted thereto by an accelerating device are utilized to cause positive actuation of tripping or releasing means to set the mechanism into operation.

Still another object of the invention is to provide a coin operated prepayment mechanism of this character in which, upon the actuation of tripping or releasing means, an energy storing device or accumulator is set into action to operate the prepayment mechanism.

Still another object of the invention is to provide a prepayment mechanism in which the operation of the coin accelerating device effects the winding of an energy storing device in the

form of a motor spring for the storage of energy to operate the prepayment mechanism.

Still another object of the invention is to provide a coin operated prepayment mechanism adapted for use with coins of different values and having selective means for adjusting and regulating the action of the mechanism for the control of dispensing means to dispense a greater or less amount of the commodity, according to the purchasing value of the deposited coin.

With these and other objects in view, the invention consists in the novel, construction, combination and arrangement of parts hereinafter fully described and claimed, and as shown in the accompanying drawings, in which:

Fig. 1 is a sectional perspective view of one form of the invention, showing only the essential parts thereof.

Figs. 2 and 3 are similar views, showing other forms of the invention.

Referring now more particularly to the structure shown in Fig. 1 of the drawings, 1 designates a wall of the casing of the prepayment meter, said wall having a coin insertion slot 2, 25 3 is the driving disk of the meter, and 4 is a control switch governing the flow or supply of current or other commodity from the vending mechanism, said switch comprising relatively fixed and movable members 4^a, 4^b, the latter being normally retracted to hold the switch open by means of a spring 25. Pivotaly mounted on the wall 1 is a controlling device in the form of a rocker arm or lever 6 having a free end portion located in line with the slot 2 and carrying 30 a roller 6' which projects partially into and guards the slot. The roller 6' is adapted to be engaged by a coin 24 inserted into the slot, under the pressure of which the arm is swung inwardly until the roller and coin assume the dotted line positions shown. A spring 5 is provided to swing the arm with a certain degree of force back to normal position when the roller and coin reach such dotted line positions so as to propel the coin downward, as hereinafter described.

45 Disposed in the casing 1 below the level of the slot 2 and rocker arm 6 is an open-topped rotary coin pocket or receptacle 7 in which is pivotally mounted an angle lever 8 normally held retracted by a spring 9 and in locking engagement with a 50 fixed stop 10. The pocket 7 is mounted on a shaft 7^a which carries a cam member 11, and said shaft is coupled by a gear train including a shaft 12 and sets of gears 12^a, 12^b with a shaft 20, which in turn is connected by suitable gearing 55 21' with the quantity control shaft 21. The cam

11 on the shaft 7^a is arranged for cooperation with the switch 4. When the coin pocket 7 is released for rotation and is rotated through the above-described gear train following the deposit of a coin therein, as hereinafter described, cam 11 is operated to move switch member 4^b against the resistance of the spring 25 into contact with the switch member 4^a to close the switch. At the same time shafts 20 and 21 are rotated to set or control the vending apparatus for dispensing a certain amount or quantity of the commodity to be dispensed in return for the deposited coin. Normally the cam 22 rests on the tail end of the detent 23 and holds its locking end tilted upward to a retracted position out of engagement with a stop pin 23'. When shafts 7^a, 20 and 21 are operated cam 22 is turned counterclockwise to operate the quantity shaft 21 and to release the detent 23 which drops down on pin 23', and cam 11 acts to move switch member 4^b to closed position. In so moving the member 4^b tilts the adjacent shouleder locking end of the detent upward and moves behind it and such end of the detent then drops downward and locks the member 4^b in closed position. On each operation shaft 12 makes a complete rotation to return the pocket 7 to normal position in which lever 8 will again engage stop 10 and cam 11 will also be returned to normal position. At the end of the dispensing action cam 22 will be rotated in a clockwise direction through the action of driving disk 3 by shaft 21 and intervening gearing, as hereinafter described, to engage and trip the detent 23 to released position, whereupon the member 4^b will be retracted by its spring 25 to open the switch.

On shaft 20, to which is fixed the gear 12^b, are also fixed a spur gear 16^a and a bevelled sun gear 13. The gear 13 forms one element of a differential gear, including therewith a planetary gear 14 and a bevelled and spur toothed sun gear 19. The gear 14 is arranged between and meshes with the gear 13 and bevelled surface of the gear 19 and is loosely mounted on an annularly bent or crank portion 20' of shaft 20 so as to be rotated by either of these gears and to traverse the other gear in a differential action, in which rotating or rotating and traversing motions it will permit operation of shaft 20 in one direction by gear 16^a and when driven by gear 19 will transmit motion to shaft 20 in the opposite direction. These gears are properly proportioned to drive the shafts 12, 20 and 21 at their proper ratios.

Gear 16^a receives motion from a motion transmitting gear 16 which is driven by a gear 17' on a motor wheel or drum 17^a loosely mounted on a shaft 17^b, to which drum and shaft are, respectively, fixed the ends of a coiled motor spring 17, forming therewith an energy accumulating device. The wheel or drum 17^a is provided with peripheral ratchet teeth 18 engaged by a pawl or dog 30, normally acting to lock the drum from movement in one direction and to permit the drum to be turned in the opposite direction. The spring is normally tensioned sufficiently to, through the shaft 12 and coacting gearing, hold pocket 7 locked in normal position. The drum is adapted to be rotated by expansion of the spring so as to transmit motion through gears 17' and 16 to the shafts 7^a, 20 and 21 to operate the working parts above described for a vending action when the lever 8 is released by the deposit of a coin.

At the end of a vending action the shaft 17^b may be operated by a suitable motor, set into action at that time, to automatically rewind the

spring 17, in which event it may be assumed that the motor employed for this purpose is suitably cut out of action when the spring is fully wound or that the motor is simply braked to a standstill by the wound-up spring. In the present instance, however, I have shown the use of means operated by the rocker arm 6 when the latter is actuated on the deposit of a coin for rotating the shaft 17^b to rewind the spring. Such means comprises a gear 27 loose on the shaft of the rocker arm and fixed to a ratchet wheel 27'. A spring pressed pawl 26 is provided on the rocker arm for engagement with the ratchet wheel to rotate the gear 27 in a motor spring winding direction when the rocker arm is swung inwardly under pressure of a coin and to allow it to rotate freely in the opposite direction. The gear 27 meshes with a gear 28 fixed on a shaft with another larger gear 28', which latter meshes with a gear pinion 29 fixed on the drum shaft 17^b, whereby, when the rocker arm is swung inwardly, the shaft 17^b will be turned in spring winding direction, in which operation the pawl 30 will hold the drum 17^a from rotation until arm 6 returns to normal position and lever 8 is released. The gears 27, 28, 28', 29 are so proportioned as to effect a full winding of the spring on an inward working movement of rocker arm 6, so that upon release of the lever 8 the drum and gear 16 will be operated to transmit motion to the respective shafts 12, 7^a, 20 and 21 for a vending operation.

On the insertion of a coin through slot 2 the rocker arm 6 will be forced inwardly. In such action portions of the periphery of a coin will bear on the roller 6 and inclined lower wall of the slot, whereby the coin will be guided until it assumes a position above the receptacle 7. On the inward swinging movement of the arm 6 the spring 5 will be tensioned and at the limit of such swinging movement the coin will be in a position to be released from engagement with the roller and slot wall, as shown in dotted lines in Fig. 1. When this occurs the spring 5 will exert its retroactive force on the arm 6 to move it back to normal position, and this force will act upon the coin to propel it downward into pocket 7 and against the lever 8, thus tripping said lever and releasing it from locking engagement with the stop 10. As the coin is propelled downward the force of its weight as well as its propulsive force are utilized to insure a positive tripping of the lever 8 against the resistance of its spring 9. The operating parts, which are normally locked from action by the motor spring 17 by engagement of lever 8 with stop 10, are now free to be operated and the motor spring, which has been tensioned in either of the ways described, will then act through the gearing previously described to rotate the pocket 7 to dump the coin and to rotate the various shafts to actuate the vending mechanism. At the beginning of this operation it will be readily understood that detent 22 will be retracted, switch 4 closed and shaft 21 set into working action, and that in rotating shaft 20 to set the parts for the vending operation gear 14 will rotate with gear 13 and travel about gear 19.

Gear 19 has formed therewith a spur gear meshing with a pinion 19' fixed on a shaft 19^a connected by gearing 19^b with the shaft of the disk 3. This disk is driven when the vending machine is in operation and operates through gears 19 and 14 to rotate shaft 20 in the reverse direction to that previously described to bring cam 22 back to normal position in which it trips

detents 23 to release the switch member 4^b, whereby the switch is opened and the vending operation stopped. In this action gear 14 is rotated by gear 18 and travels about gear 13.

The structure disclosed in Fig. 1 is designed for the use of a coin of a predetermined value. The device, however, can be used in connection with coins of different values, as illustrated in the embodiment of the invention disclosed in Fig. 2. In this embodiment a stationary coin pocket or chamber 31 is provided to receive the coin from the slot 2, which chamber includes an inner wall portion 32 and a movable bottom or coin retaining plate 33. The rocker arm 6^b in this construction is held in normal position by a spring 5^b and carries at one end a pivoted abutment or guard plate 34 which normally closes the slot 2 and is free to swing between spaced stops 35, 36 on the arm. A feeler 37 extends into the chamber 31 so as to be engaged by coins introduced thereinto, and this feeler is hinged to the axis of the rocker arm and coupled to the arm by a bent portion 38 free for unilateral motion. A bell-crank lever 39 has one of its arms 40 arranged to lie in contact with the feeler and has its other arm 40' coupled to an axially movable gear 41 which meshes permanently with and is slidably along a broad gear 42 which drives the quantity shaft 21^b. The feeler 37 is movable to different positions by different sized coins and moves the bell crank lever 39 correspondingly to adjust the gear 41 along the gear 42 and into engagement with any one of a plurality of mutilated gears 43, 44, 45 to transmit, through interposed gearing, a greater or less degree of motion to a rotary control disk 46 fixed to a shaft 47 carrying a gear pinion 48.

The gears 43, 44, 45 represent different coin values and are designed to control the operation of the vending device to dispense an amount of the commodity proportionate to the value of the deposited coin. It may be assumed for this purpose that gear 43 is toothed about half its circumference and gear 44 about its entire circumference, while gear 45 is provided with one tooth only. The gear 48 meshes with a gear 48' fixed to the outer end of a coiled motor spring 49, which spring is fixed at its inner end to a ratchet wheel 50 with which cooperates a check pawl 51 mounted on a fixed part of the machine and a feed pawl 52 mounted on the lever 39. The lever 39, gear 48' and ratchet wheel 49 are loosely mounted on the shaft or axis 39' of the lever 39, so that when motion is transmitted to lever 39 in a counter-clockwise direction the spring 49 will be wound up by action of pawl 52 on the ratchet wheel and gear 41 moved to engage one or the other of the gears 43, 44, 45 according to the extent of movement of lever 39, pawl 51 holding the ratchet wheel from reverse movement. When the spring 49, which is normally held from operation, is released for operation, gears 48, 48' rotate shaft 47 to rotate the disk 46. This disk carries a pin 58 which, when the disk is rotated in the direction of the arrow, closes a switch 4 of the construction previously described which governs the flow or feed of the commodity from the vending apparatus. In so doing arm 4^b of the switch is moved behind a pawl 23^b which holds the switch closed until the amount of the commodity paid for has been dispensed. This pawl 23^b at the end of the dispensing operation is retracted by suitable means operated in practice by or from the vending apparatus.

The means for holding the energized motor and shaft 47 from operation until released for

operation comprises a cam disk 53 in gear with the disk 46 and mounted on a shaft 53', said disk 53 being provided with a stop tooth 53^a. On the shaft 53' is also a detent 55. The tooth 53^a is adapted to engage the lower end of a trip lever 53^b mounted to swing laterally on a shaft 53^c. At its upper end the lever 53' is provided with a cam projection 54 lying above and at one side of the plate in the path of a coin impelled downward into contact with said plate. In the normal position of the parts, and in the absence of a coin engaging the plate, the lever 53^b engages the tooth 53^a and locks the disk and consequently the disk 46, shaft 47 and motor driven gear 48' from rotation. The detent 55 is adapted to engage a cam faced portion 56 at the lower end of a lever 57 mounted on a shaft 57' and to the upper end of which the plate 33 is fixed. The plate is adapted to swing laterally on the shaft 57' under the weight and impact of a coin striking it so as to disengage the cam 56 from the detent 55 which assists in locking the disk 53 from rotation, whereby in the tilting operation of the plate the coin will be dumped and pass from the chamber into a suitable receiver. The upper end of the lever 53^b carrying the cam projection 54 lies at one side of the plate 33 in its direction of rotation, so that when the coin strikes the projection 54 and the plate the lever 53^b will be swung out of engagement with the tooth 53^a and the cam 56 of lever 57 will be disengaged from the detent, whereby the disk 53 will be released to allow the motor to operate the shaft 47 and the plate 33 will be tilted to dump the parts 33 and 53^b will swing by gravity back to normal position and upon the return of the disk 53 to normal position such parts will again be locked against movement until operated by a coin.

On the insertion of a coin through slot 2 the pressure of the coin will swing the arm 6^b to a greater or less extent upwardly, depending on the diameter of the coin and as the coin passes downward it will engage the feeler 37 by which the lever 39 will be moved to a greater or less extent to shift the gear 41 and tension the motor spring. At the same time spring 5^c will be tensioned so that as soon as the coin is free to move past the lower edge of slot 2 and the guard plate and introducing pressure is removed from the coin the reaction of the spring 56 will return the arm 6^b to normal position and the coin will be impelled with force against the plate 33 and projection 54 to set the motor into action. The vending apparatus having been set for operation, the parts 37, 39, 47 and 46 are returned to normal position by gravity of the parts 37, 39 or by gearing operated by the vending machine and acting on shaft 47, leaving the switch 4 closed while the vending operation is going on and until it is opened by the vending means at the close of the vending operation.

In the embodiment of the invention shown in Fig. 3 there is provided, as in Fig. 1, a rotary coin pocket 7^c, and a coin actuated locking and releasing lever 8 coacting with a fixed stop 10. The coin slot 2 in this construction is closed or guarded by a pair of rollers 58 mounted on the free ends of levers 59 and 60. These levers are coaxially supported at their opposite ends and connected and moved toward each other by a spring 5^c. The lever 59 is fixed to a sun wheel 59' and freely movable therewith about a shaft 61, while the lever 6 is fixed to said shaft. The wheel 59' meshes with a planetary gear 62 rotatable about a cranked portion 62' of the shaft

and meshing with a sun wheel 63 fixed to the shaft, said gears 59', 62 and 63 forming a differential gear transmission.

Crank arm 64 is fixed to the shaft 61 and carries a pawl 65 which engages a ratchet wheel 66. This ratchet wheel is locked against backward motion by a pawl 67 and is connected by suitable gearing 68 with a motor spring 69 representing the energy accumulator for operating the apparatus, with which spring the rotary coin pocket 7 is likewise connected through suitable gearing 70 connecting the motor spring with the shaft 7 on which the pocket 7^c is mounted.

On the shaft 70' is fixed a sun wheel 71 of a differential gear including a planetary gear 72 and a sun wheel 73. The gear 72 is mounted to turn on a cranked portion 72' of the quantity shaft 21 on which the sun wheel 73 is loosely mounted, which gear 73 is adapted to be driven by the driving disk 3 of the meter. The sun wheel 71 carries a pin 74 controlling the switch 4 of the prepayment apparatus. 23^c is a pawl which engages switch arm 4^b to hold the switch 4 closed. This pawl is provided with an arm 75 which cooperates with a rigidly mounted cam or arm 76 on the quantity shaft 21. 77 designates a stationary channel for guiding the coin to the pocket 7^c.

The just described arrangement, like that of the first form of embodiment, is intended for one kind of coin only. When a coin is pushed into the slot 2, the rollers 58 are spread apart and tension the spring 5^c. By this means the sun wheel 59' and the planet wheel 62 are moved and act upon the sun wheel 63 to cause the pawl 65 to rotate the wheel 66, thus winding up the motor spring 69. When the coin has passed the supporting points on the rollers 58, the tensioned spring 5^c reacts and causes the rollers to impel the coin through the guide channel 77 and into the pocket 7^c. Therein the coin strikes the lever 8 and releases the pocket for rotation by the spring 69 and causes the closure of the switch 4 by the pin 74 and the adjustment of the quantity shaft 21 to an amount of commodity corresponding to the value of the coin. Upon the closing of the switch 4 the pawl 23^c locks it and keeps it closed until at the close of the vending operation and the action of the driving disk 3 the arm 76 engages the arm 75, thereby releasing the pawl 23 so that the switch 4 is allowed to open.

The invention may be used for dispensing commodities other than electricity, e. g., gas or water.

It will be understood that the embodiments of the invention herein shown and described have been given only by way of example and that the details thereof may be modified within the scope of the appended claims without departing from the spirit of the invention.

Instead of securing the rollers directly to the levers they may be mounted for movement in paths extending parallel with the slot 2 and slidably connected with the levers, so that the supporting points of the coin on the rollers would always be at the same distance from the slot, adapting the apparatus to be made for coins of small dimensions, as such arrangement would allow the coins to be inserted far enough into the slot to pass beyond their supporting points on the rollers.

Due to the fact that the energy due to the accelerated motion of a coin propelled into the apparatus as well as its weight are utilized to effect the release of the coin pocket and the motor

to set the apparatus into operation, the coin passage may be arranged for the travel of the coin either a long distance or a short distance, with the advantage in the latter case of permitting an apparatus of small dimensions to be built without loss of efficiency. The positive propulsion of the coin in a downward direction also adds the weight of the coin to its striking force against the trip lever in the coin pocket, insuring a positive release of this lever.

Having thus described my invention, I claim:

1. In a prepayment mechanism of the character described, a casing having a coin insertion slot, controlling means for governing the operation of a dispensing mechanism, a motor, normally deenergized power supplying means for driving the motor, an element adapted to be engaged and moved by the inserted coin, to energize the power supplying means for a motor driving action and to thereafter release the coin, a second element adapted to be engaged by the coin released by the first named element and movable by the action of the motor to release the coin, locking means for normally holding the motor from action and said second named element from coin releasing movement, said locking means adapted to be freed for coin releasing movement by the deposited coin, and means operated when the locking means is released and the motor set into action for operating the controlling means.

2. In a prepayment mechanism of the character described, a casing having a coin insertion slot, controlling means for governing the operation of a dispensing mechanism, a motor, normally deenergized power supplying means for driving the motor, an element disposed beneath the slot and adapted to be engaged by the deposited coin and movable by the action of the motor to release the coin, an element arranged in line with the slot and operative by the inserted coin to energize said power supplying means for driving the motor, locking means for normally holding the motor from action and the first named element from coin releasing movement, means acting on the second named element after the energization of the power supplying means thereby to cause the same to impel the deposited coin downward against said first named element and in engagement with the locking means to release the latter, and means operated when the locking means is released and the motor set into action for operating the controlling means.

3. In a prepayment mechanism of the character described, a casing having a coin insertion slot, controlling means for governing the operation of a dispensing mechanism, a motor, normally deenergized power supplying means for driving the motor, an element adapted to be engaged by the inserted coin and movable by the action of the motor to release the coin, means for impelling the inserted coin against said element and simultaneously energizing and rendering said power supplying means operative to drive the motor, locking means for normally holding the motor from action and said element from coin releasing movement, said locking means being adapted to be released by the deposited coin, and means operated when the locking means is released and the motor set into action for operating the controlling means.

4. In a prepayment mechanism of the character described, a casing having a coin insertion slot, controlling means for governing the operation of a dispensing mechanism, a motor, a rotary pocket to receive the inserted coin and ro-

tatable by the action of the motor to release the coin, locking means for normally holding the motor from action and said pocket from rotation, said locking means being adapted to be freed by the deposited coin in the pocket, and means operated when the locking means is released and the motor set into action for operating the controlling means.

5. In a prepayment mechanism of the character described, a casing having a coin insertion slot, controlling means for governing the operation of a dispensing mechanism, a motor, normally deenergized power supplying means for driving the motor, a coin retaining element adapted to be engaged by the inserted coin and movable by the action of the motor to release the coin, means operative under pressure of the inserted coin for energizing and rendering the power supplying means operative to drive the motor and for thereafter impelling the coin against said element, locking means for normally holding the motor from action and said element from coin releasing movement, said locking means adapted to be freed by the contact therewith of the coin impelled into engagement with the retaining element, and means operated when the locking means is released and the motor set into action for operating the controlling means.

6. In a prepayment mechanism of the character described, a casing having a coin insertion slot, controlling means for governing the operation of a dispensing mechanism, a motor, normally deenergized power supplying means for driving the motor, an element adapted to be engaged by the inserted coin and movable by the action of the motor to release the coin, means movable under pressure of the inserted coin for energizing and rendering the power supplying means operative for the motor and adapted to be energized by its movement for impelling the coin following the energization of the power supplying means against said element, locking means for normally holding the motor from action and said element from coin releasing movement, said locking means adapted to be freed by the contact therewith of the coin impelled into engagement with the retaining element when the locking means is released and the motor set into action for operating the controlling means.

7. In a prepayment mechanism of the character described, a casing having a coin insertion slot, controlling means for governing the operation of a dispensing mechanism, a coiled spring motor, a rotary pocket adapted to receive the inserted coin and rotatable by the action of the motor to release the coin, means movable under pressure of the inserted coin for tensioning the motor spring for action and adapted to be energized by its movement for impelling the coin into the pocket, locking means for normally hold-

ing the motor from action and the pocket from rotation, said locking means adapted to be freed by the impelled coin into the pocket, and means operated when the locking means is released and the motor set into action for operating the controlling means.

8. In a prepayment mechanism of the character described, a casing having a coin insertion slot, controlling means variably movable so as to 10 be set to variably govern the operation of a dispensing mechanism, a motor, an element adapted to be engaged by an inserted coin of any one of a plurality of denominations and movable by the action of the motor to release the coin, locking means for normally holding the motor from 15 action and said element from coin releasing movement, said locking means adapted to be freed by the deposited coin, means operated by inserted coins of different denominations for variably setting the controlling means, and means operated when the locking means is released and the motor set into action for operating the controlling means.

9. In a prepayment mechanism of the character described, a casing having a coin insertion slot, controlling means for governing the operation of a dispensing mechanism, a coiled spring motor, an element adapted to be engaged by the inserted coin and movable by the action of the motor to release the coin, means movable under pressure of the inserted coin for tensioning the motor spring for action and adapted to be energized by its movement for impelling the coin into engagement with said element, locking means for normally holding the motor from action and said element from coin releasing movement, said locking means adapted to be freed by the impelled coin, and means operated when the locking means is released and the motor set into action for operating the controlling means.

10. In a prepayment mechanism of the character described, a casing having a coin insertion slot, controlling device for governing the dispensing operation of a dispensing mechanism, a 25 controlling switch, a coiled spring motor, an element adapted to be engaged by the inserted coin and movable by the action of the motor to release the coin, means movable under pressure of the inserted coin for tensioning the motor spring 30 for action and adapted to be energized by its movement for impelling the coin into engagement with said element, locking means for normally holding the motor from action and said element from coin releasing movement, said locking means adapted to be freed by the deposited coin, and means operated when the locking means is released and the motor set into action 35 for operating the controlling device and closing the switch.

PAUL MOOS.
